CLAIM

The ornamental design for an electric motor housing, as shown and described.

DESCRIPTION

FIG. 1 is a front/top side perspective view of the electric motor housing according to my design;

FIG. 2 is a left side view with the top side oriented up thereof;

FIG. 3 is a front view with the top side oriented down thereof;

FIG. 4 is a right side view with the top side oriented to the right thereof;

FIG. 5 is a back side view with the back side oriented to the left thereof;

FIG. 6 is a bottom view thereof; and,

FIG. 7 is a top view thereof.

In the drawings, the broken lines shown in FIG. 5 form no part of the claimed design.
